UNITED STATES PATENT OFFICE.

ALEXANDER NYMAN, OF SWISSVALE, PENNSYLVANIA, ASSIGNEE TO WESTINGHOUSE ELECTRIC & MANUFACTURING COMPANY, A CORPORATION OF PENNSYLVANIA.

TELEPHONE DEVICE.

Application filed September 20, 1923. Serial No. 663,787.

My invention relates to sound reproducing apparatus, having particular relation to telephone transmitters or receivers.

One object of my invention is to provide a new embodiment of a loud speaking device wherein signal currents are faithfully translated into sound waves or, vice versa, without distortion.

Another object of my invention is to provide sound reproducing apparatus wherein the vibratory elements are caused to move in a substantially rectilinear direction only, thereby avoiding many of the well-known undesirable effects which arise from lateral thrusts.

A further object of my invention is to provide apparatus, of the class described above, which is characterized by extreme simplicity of arrangement and by accessibility of the parts requiring adjustment, which can be inexpensively manufactured in quantity and the several parts of which may be easily made by existing automatic machinery and assembled with a minimum expenditure of time.

According to my invention, I provide a telephone transmitter comprising a solenoid which has a polarizing coil energized by unidirectional currents and signal-current coils for varying the point of maximum field intensity of the polarizing coil. An armature member is disposed within the solenoid at the point of maximum field intensity and it is adapted to move in the axis of the solenoid in accordance with the variations in the position of said point of maximum field intensity. The resulting vibrations of the armature or core member may be translated into sound waves through a diaphragm 40 which is operatively associated therewith.

With these and other objects and applications in mind, my invention further consists in the details of construction and operation and circuit arrangement hereinafter described and claimed and illustrated in the accompanying drawing wherein,

Figure 1 is an enlarged longitudinal sectional view of a telephone device embodying my invention taken on the line 1—1 of Fig. 2, and

Fig. 2 is a top plan view of the structure of Fig. 1.

In the illustrative embodiment of my invention shown in the drawings, a magnetic circuit is provided including a tubular member 1 and annular end members 2 and 3, all of iron or other magnetizable material. Through the openings 4 and 5 in the end members extends a hollow bobbin 6 on which the coils 7, 8 and 9 are wound. The polarizing coil 7 may be energized from a source 11 of direct current energy through conductors 12 and 13. The series-connected signaling current coils 8 and 9 may be energized by any current which it is desired to translate into sound waves. The source of such current is not shown in the drawing. The relative directions of the windings of the signaling current coils are such that the flux due to one of them is opposed to that due to the other for reasons which will appear more fully hereinafter.

An armature or core member 14 is disposed within the polarizing coil 7 of the solenoid substantially at the point of maximum field intensity. Preferably, this armature is of a cylindrical form with recessed ends. A link 15, secured to the middle of the diaphragm 16 is fastened to the bottom of the upper recess in any desired way. The diaphragm 16 is disposed immediately over the upper end portion 2 of the casing 1 and is supported at its periphery between resilient washers 17 and 18 which, in turn, are carried by a nonmagnetizable frame 19 secured to the upper portion of the casing 1.

Secured in any desired way at the apex of the lower recess in the armature 14, is a rubber thread 21 or other resilient connection. The lower end of the connection is fastened to a screw 20, adjustably mounted in an arm 22 on the lower end portion 3. It is to be understood that my invention is not strictly limited to the particular means described for constraining the motion of the armature 14 to the longitudinal axis of the solenoid, but that any means may be employed, as, for instance, a rigid member extending from the armature 14 through a bearing in the supporting arm 22. In order to sim-

plify the description of the construction and operation of my invention, I have omitted from the drawing such portions of the general structures as are well known to those skilled in the art.

The operation of the instrument embodying my invention is based upon the fact that a magnetizable armature member, which is disposed within a magnetizing coil, tends to assume a position wherein it embraces a maximum number of lines of force. Hence, when the polarizing coil 7 of the solenoid is energized by currents from the source 11 of direct current energy, the armature member 14 assumes a position within the coil 7 where it embraces a maximum number of lines of force established by said coil 7. The length of the connecting link 15 is such as to position the armature 14 at the point of maximum field intensity established by the polarizing coil 7 when no current flows in coils 8 and 9. Consequently, under these conditions, the armature member 14 remains in its neutral position and is not affected by the energization of the polarizing coil 7 alone.

Assume for the sake of clearness that the flux established by the direct current in coil 7 is upward and consider a moment when current in the coil 8 also gives an upward flux. At the top of the armature 14 the flux due to coil 7 and that due to coil 8 reinforce each other at this moment. Therefore, an increase of field strength occurs there. Because the coils 8 and 9 are connected to produce opposed fluxes, the flux due to the coil 9 is downward at this moment and so a diminution of field strength occurs at the lower end of armature 14. The armature 14 therefore moves upward in order to occupy the point of maximum field intensity. On the other hand, when the currents through the series-connected windings 8 and 9 are reversed, the point of maximum field intensity is lowered an amount corresponding to that by which it was just raised. Accordingly, a force is exerted on the armature 14 causing the same to move an equal distance in the opposite direction.

Hence, it can readily be seen that when the signal current coils 8 and 9 are energized by periodic electric energy, such as obtains, for instance, in currents modulated in accordance with sound waves, the armature member 14 is caused to vibrate in accordance with the variations in the energizing currents. The vibratory motion of the armature member 14 being transferred to the diaphragms 16 through the connecting link 15, sound waves of corresponding vibration frequency ensue.

While I have shown and described a specific embodiment of my invention, for the purpose of illustrating the underlying principles and theory of operation thereof, it is

apparent that various changes and modifications may be made therein without departing from the spirit of my invention. I desire, therefore, that only such limitations shall be imposed thereon as are indicated by the appended claims or as are demanded by the prior art.

I claim as my invention:

1. In a translating device, a solenoid comprising a polarizing coil, and additional signal-current coils, a movable core therefor, and a diaphragm operatively associated with said core, whereby said diaphragm will be vibrated in accordance with such currents as are supplied to said signal current coils.

2. The combination with a solenoid comprising a polarizing coil and signal-current coils for reciprocally varying, along the axis of said solenoid, the point of maximum field intensity, of a vibratably positioned armature adapted to move according to the variation in position of said point of maximum field intensity, and a diaphragm operatively associated with said core.

3. In combination, a solenoid comprising a coil, a source of unidirectional current for energizing said coil, said solenoid also having coils positioned on opposite sides of said first-mentioned coil, a source of signal currents for energizing said coils, said signal-current coils being so connected that the fluxes established by them are opposed, an armature member for said solenoid so positioned as to vibrate in accordance with the varying intensity of the signal currents supplied to said signal-current coils, and a diaphragm operatively associated with said armature member.

4. In combination, a solenoid comprising a coil, a source of unidirectional current for energizing said coil, said solenoid also having coils positioned on opposite sides of said first-mentioned coil, a source of signal currents for energizing said coils, said signal-current coils being so connected that the fluxes established by them are opposed, a diaphragm, an armature member suspended from said diaphragm and positioned within said solenoid whereby it will vibrate in accordance with the varying intensity of the signal currents traversing said signal-current coils, and means for constraining the motion of the armature to the axis of the solenoid.

5. In a telephone receiver, a signal-receiving circuit including two coils wound and positioned to produce opposing fluxes, and a flux-responsive device located between said coils said device being arranged for translational movement along an axis common to said coils.

6. In a telephone receiver, a signal-receiving circuit including two coaxial coils spaced apart and wound to produce opposed fluxes in the space between them, a magnetic mem-

ber in said space and means for polarizing said member said member being arranged for translational movement along an axis common to said coils.

5 7. In a telephone receiver, a signal-receiving circuit including two coaxial coils spaced apart and wound to produce opposed fluxes in the space between them, a magnetic member coaxial with said coils and means constraining said member to move along the common axis.

8. In a telephone receiver, a signal-receiving circuit including two coaxial coils spaced apart and wound to produce opposed fluxes 15 in the space between them, a magnetic member coaxial with said coils, means constraining said member to move along the common

axis, means for polarizing said member and a sounding device operatively connected to said member.

20

9. In a telephone receiver, a signal-receiving circuit including two coaxial coils spaced apart and wound to produce opposed fluxes in the space between them, a magnetic member coaxial with said coils, means constraining said member to move along the common axis, means for polarizing said member and a sounding device operatively connected to said member, said connection constituting a part of the constraining means.
